(57) **CLAIM**

The ornamental design for a high density catheter tip, as shown and described.

DESCRIPTION

FIG. 1 is a perspective view of a high density catheter tip showing our design;

FIG. 2 is left elevation view thereof;

FIG. 3 is a right elevation view thereof;

FIG. 4 is a rear elevation view thereof;

FIG. 5 is a front elevation view thereof;

FIG. 6 is a top plan view thereof;

FIG. 7 is a bottom plan view thereof; and,

FIG. 8 is another perspective view thereof, showing our new design in a flexed position.

The S-shaped dot-dash broken lines in the drawings define the boundaries of the claimed design and form no part thereof. The remaining dashed broken lines in the figures depict portions of the catheter tip that form no part of the claimed design.

1 Claim, 4 Drawing Sheets
